UNITED STATES PATENT OFFICE.

JAMES A. RAMUS, OF MINNEAPOLIS, MINNESOTA.

MARGIN-STOP MECHANISM FOR TYPEWRITERS.

Application filed October 17, 1925. Serial No. 63,016.

This invention relates to typewriters and especially to margin stop mechanisms therefore, capable of being employed on many standard makes of typewriters now commercially sold.

It is the main object of the invention to provide simple but highly efficient margin stop mechanism co-operating with several parts of a standard typewriter to permit the margin stop on the typewriter to be automatically set by the manipulation of a single release lever and the movement of the sliding carriage.

Another object of the invention is to provide margin stop mechanism operatively connected with the carriage release lever on certain types of standard typewriters adapted to cause the margin stop to releasably interlock with the center stop of the typewriter, whereby the movement of the sliding carriage will cause the margin stop to be set as desired.

A further object of the invention is to provide such a device operative from the carriage of the typewriter by means of a control lever, employing a margin stop with a latch carried thereby, adapted to interlock with the center stop of the typewriter and to also release the margin stop from the margin stop rod, and an operating lever pivoted on the escapement frame and adapted to engage said latch, whereby the carriage may be moved to set the margin stop as desired.

These and other objects will be apparent from the following description made in connection with the accompanying drawings, wherein like characters refer to similar parts throughout the several views, and in which,

Fig. 1 is a plan view of the carriage and adjacent parts of a standard form of typewriter, with the improved margin stop mechanism thereon;

Fig. 2 is a cross section on a larger scale taken on the line 2-2 of Fig. 1;

Fig. 3 is a cross sectional view showing the latch member on the margin stop in inter-engagement with the center post;

Fig. 4 is a fragmentary plan view showing a control lever and a portion of one of the margin stops;

Fig. 5 is a side elevation of the control lever;

Fig. 6 is a side elevation on an enlarged scale of the operating dog carried by the top of the control lever; and

Figs. 7 and 8, respectively, are a plan and side elevation of the preferred form of margin stop employed.

While the invention is applicable to several types of standard typewriters, such as the L. C. Smith, the Woodstock, the Remington Monarch and the Demountable, the preferred embodiment thereof is herein illustrated as being applied to the standard type of typewriter manufactured by the Royal Typewriter Company.

In the drawings, the carriage is illustrated as supported by means of the usual bottom rail 10, (indicated in Fig. 1 in the dotted lines) and by means of the carriage roll 70 guide rod 11 engaged on opposite sides by means of the carriage rolls 12 pivotally mounted to the upper end of the escapement frame 13. The carriage ends 14 have secured therebetween, in the usual manner, 75 the platen or printing cylinder 15 controlled by the cylinder knobs 15^a, as well as the carriage roll guide rod 11 and the margin stop rod 16 spaced parallel and slightly to the rearward side of rod 11. The usual 80 rack rail 17, having outwardly extending arms 17^a at each end thereof, is normally held in engagement with the escapement pinion 18 by means of coiled springs 19 interposed between the outer ends of arms 17^a 85 and the margin stop rod disposed thereabove. Rack rail 17 fulcrums on pivot screws 17^b secured to the carriage ends 14, and may be elevated to release the carriage by means of the carriage or rack release 90 levers 20 extending forwardly at either end of the carriage. The escapement frame 13 carries the usual tabulator-rack-lift-lever-fulcrum-screw 21. The usual center stop 22 on the type of typewriter illustrated is secured to the main typewriter frame provided with the line lock lever 22^a normally spaced therefrom. In the Royal typewriter the line lock lever 22^a is preferably bent outwardly 95 somewhat before installing the improved margin stop mechanism in order that the spaced relation between said lever and the center stop 22 may be present when the carriage is in extreme left position. As will

be later shown in the operation of the preferred form of the invention, this slot or recess is necessary.

All of the parts hitherto described are standard parts of the Royal typewriter and the cooperation of several of these parts, with the added elements of the margin stop mechanism, make possible the successful device hereinafter described.

- 10 In the embodiment of the invention designed for the Royal typewriter, as illustrated, as well as in most types of standard typewriters, right and left margin stops are employed identically constructed and having 15 the body portion 23 of U-shaped cross section slideable on margin stop rod 16, carrying at one side thereof the adjustable abutment screw 23^a adapted to engage center stop 22 to limit the movement of the carriage in one 20 direction. It will be noticed (see Fig. 1) that when said margin and center stop are mutually engaged, the engaged surface of center stop 22 is disposed substantially centrally of the margin stop. Due, however, 25 to the particular control mechanism for practically all types of standard typewriters when the carriage has been moved to the extreme right and released there is a small amount of play between center stop 22 and 30 the abutment screw 23^a of the left-hand margin stop. To take up this play and mutually engage said stop elements, the carriage must be held to its extreme right position. Applicant provides his margin stops with vertically swinging margin stop levers 24 extending longitudinally of body members 23 and fulcrumed adjacent the inner ends thereof. Levers 24 are provided at their outer ends with the pivoted retaining pawls 40 25, adapted to engage teeth 16^a on the margin stop rod 16, whereby the margin stop may be set in a desired position on said rod or released therefrom for setting. Each margin stop is provided with a transversely 45 disposed vertically swinging latch 26 having depending arms disposed at either side of body member 23 and pivoted adjacent one side of said body member. The intermediate or body portion of latch 26 is disposed beneath margin stop lever 24 and is adapted to lift said lever when said latch is swung. Simultaneously with this action, when the carriage is held in either extreme 50 right or left position, the rearwardly disposed depending arm of latch 26 will be projected between center stop 22 and line lock lever 22^a, interlocking the margin stop with the center stop 22. Thus, when the stop members are mutually engaged, the latch 26 55 will be aligned to interlock said members and release the margin stop from the margin stop rod 16.

To actuate the said latch on the Royal typewriter, a substantially V-shaped operating lever 27 is provided preferably ful-

crumed at the vertex of the V on the tabulator-rack-lift-lever-fulcrum-screw 21 disposed on the escapement frame 13. The lower or forward end of operating lever 27 is extended forwardly and has a small roller 27^a 70 carried at its outer end, adapted to normally contact the upper surface of the rack rail 17. The rear or working arm of lever 27 is extended upwardly and substantially at right angles at its outer end, best shown in Fig. 4, 75 terminating in the upstanding ear 27^b to which a vertically swingable operating dog 28 is pivoted, spring-pressed normally into elevated position. Operating lever 27 is resiliently held in contact with rack rail 17 80 by means of the coiled spring 29 disposed about said tabulator-rack-lift-lever-fulcrum-screw 21. The working arm of lever 27 is formed, as described and illustrated, in order that the operating dog 28, carried at the 85 upper end thereof, may be aligned with the forward depending arm of one of the latches 26 on the margin stops when the center stop 22 and one of the abutment screws 23^a on the margin stops are mutually engaged by 90 holding the carriage in extreme left or right positions.

Operation.

When it is desired to set the left margin 95 stop, the typewriter carriage is first moved to its extreme right position, the normal play between center stop 22 and left margin stop being taken up to mutually engage said stop elements in the manner previously described. The latch 26 will then be aligned with the operating dog 28 on lever 27, and, at its rearward end, with the slot between center stop 22 and line lock lever 22^a. The rack or carriage release lever 20 is then depressed, 100 thereby elevating rack rail 17, and, in turn, swinging lever 27 backwardly. Operating lever 27, as has been previously described, is actuated by the rack release lever and, obviously, actuates the forward arm of latch 110 26, swinging said latch to simultaneously release the margin stop lever 24 and to releasably inter-lock the left margin stop with center stop 22. The left margin stop is now free to move with reference to margin 115 stop rod 16 and is also rigidly inter-locked with the center stop 22. The carriage may then be moved to any desired point in line of writing, obviously moving margin stop rod 16 relatively to said left margin stop and, when the rack or carriage release lever 20 is released, the operating lever 27 and latch 26 will again take their normal positions and the left margin stop will be automatically set at the point desired. 120 125

In setting the right margin stop, carriage release lever 20 must first be depressed to permit movement of the carriage to the left. The carriage is then moved to extreme left position, at which time the abutment screw 130

23^a on the right margin stop will engage the line lock lever 22^a of center stop 22. Since standard typewriter carriages are normally impelled to the left, there will be no play between the stop elements when the carriage is in the above stated position, and the latch 26 on the right hand margin stop will be aligned with operating lever 27 and with the slot between center stop 22 and line lock lever 22^a. However, inasmuch as it was necessary to depress the carriage release lever 20, in order to move the carriage to the extreme left, the operating dog 28 was moved rearwardly before the carriage was moved, sliding behind the forward depending arm of latch 26, as the carriage reached its extreme left position. To return operating dog 28 to normal position for operating latch 26, it is only necessary to release carriage release lever 20, which permits lever 27 to swing forwardly, camming the spring-pressed dog 28 to the forward side of latch 26. When the carriage or rack release lever 20 is again depressed, operating dog 28 will again engage the latch 26, freeing the right margin stop from margin stop rod 16 and simultaneously interlocking the right margin stop with center stop 22. The carriage may be then moved to a desired position in line of writing and the rack release lever released to set the margin stop automatically as desired.

While the embodiment of the invention illustrated is especially designed for a Royal typewriter, it will be readily seen that by slight changes in the form and details, the invention may be applied to other types of machines such as the L. C. Smith, Woodstock, Demountable, and Remington Monarch. All of these machines employ right and left margin stops settable on horizontally extending margin stop rods and a center stop or center stops cooperating therewith to limit the movement of the carriage. Several of these machines, however, mount their margin stop rod on the typewriter frame and their center stop on the carriage. All standard types employ a carriage release lever of some kind. It will be seen that devices within the scope of the invention may easily be designed for all standard types of typewriters and will employ the latch and inter-locking mechanism disclosed and operatively connected to the carriage release lever or an independent operating lever to set the left or right hand margin stop when the carriage has been moved to either extreme left or right positions. The operation of the device applied to other standard types of machines will be identical with the operation above described.

From the foregoing description, it will be apparent that the applicant has invented an extremely simple but highly efficient margin stop mechanism adapted to automatically

set right or left margin stops by the manipulation of a single operating lever in cooperation with the movement of the typewriter carriage.

It will, of course, be understood that various changes may be made in the form, details, proportions, arrangement of parts and application of the same without departing from the scope of the invention.

What is claimed is:

1. In a typewriter having a movable carriage, a stop element supported on said carriage, a second stop element supported independently of said carriage in position to engage said first mentioned stop element, one of said stop elements being adjustable on its support, laterally projectable means on one of said stop elements adapted to releasably fix said stop elements together whereby the position of said variable stop element may be changed and set by the movement of said carriage.

2. In a typewriter having a movable carriage, a stop element supported on said carriage, a second stop element supported independently of said carriage in position to engage said first mentioned element, one of said stop elements being adapted to be set at various positions on its support, means for releasing said variable stop element from its support, means for releasably interlocking said stop elements, whereby the position of said variable stop element may be changed by the movement of said carriage and means for resetting said variable stop element in any position on its support.

3. The structure set forth in claim 2, and an operating lever adapted to control said several means.

4. In a typewriter having a movable carriage, a stop element supported on said carriage, a second stop element supported independently of said carriage in position to engage said first mentioned element, one of said stop elements being adapted to be set at various positions on its support, a latch on said variable stop element capable of interlocking with said other stop element when said elements are mutually engaged, and means for operating said latch whereby the position of said variable stop element may be changed and set by the movement of said carriage.

5. The structure set forth in claim 4, releasable means for locking said variable stop member in a plurality of positions on its support, said latch being operative to also release said means.

6. In a typewriter having a movable carriage, a stop element supported on said carriage, a second stop element supported independently of said carriage in position to engage said first mentioned stop element, one of said stop elements being adjustable on its support, laterally projectable means

- on one of said stop elements adapted to releasably fix said elements together, and means for simultaneously releasing said adjustable stop element from its support whereby said adjustable stop element may be adjusted and set by the movement of said carriage.
7. In a typewriter, the combination with a sliding carriage, a margin stop rod and a center stop, of a margin stop mechanism comprising a margin stop adapted to engage said center stop to limit the movement of said carriage in one direction, and capable of being moved and set at various positions on said margin stop rod, means for releasably interlocking said margin stop with said center stop when said members are mutually engaged, and means for releasing said margin stop for movement on said margin stop rod whereby said margin stop may be moved and set as desired by the movement of said carriage.
8. In a typewriter, the combination with a sliding carriage, a margin stop rod and a center stop, of margin stop mechanism comprising a margin stop adapted to engage said center stop to limit the movement of said carriage in one direction, a releasable retaining means carried by said margin stop, and a latch also carried by said margin stop adapted to actuate said retaining means and to releasably interlock said margin stop with said center stop when said members are mutually engaged, whereby said margin stop may be moved and set as desired on said margin stop rod by the movement of said carriage.
9. The structure set forth in claim 8 and an operating lever controllable from an accessible point on said typewriter adapted to actuate said latch when said margin stop and said center stop are mutually engaged.
10. In a typewriter, the combination with a sliding carriage, a margin stop rod, and a rack rail, of margin stop mechanism comprising a settable margin stop slidably mounted on said margin stop rod adapted to engage said center stop, means on said margin stop for releasably interlocking with said center stop when said stop members are mutually engaged, and means connected to said rack rail for operating said interlocking means, whereby, when said rack rail is raised, said margin stop may be set at a desired position on said margin stop rod by the movement of said carriage.
11. In a typewriter, the combination with a sliding carriage, a margin stop rod, a center stop, a rack rail, and an escapement frame, of margin stop mechanism comprising a margin stop mounted on said margin stop rod, a latch carried by said margin stop adapted to releasably interlock with said center stop, a lever pivoted to said escapement frame having an arm adapted to engage said latch and connected to said rack rail for movement therewith, whereby, when said lever and latch are aligned, said margin stop may be releasably interlocked with said center stop by elevating said rack rail and said margin stop may then be moved and set at a desired position on said margin stop rod by the movement of said carriage.
12. In a typewriter having a movable carriage, a carriage release lever, a stop element supported on said carriage, a second stop element supported independently of said carriage in position to engage said first mentioned element, one of said stop elements being adapted to be set at various positions on its support, means for releasably interlocking said stop elements when the same are mutually engaged and operating means connected to said carriage release lever, whereby the position of said variable stop element may be changed and set automatically by the manipulation of the carriage release lever and the movement of said carriage.
13. In a typewriter, the combination with a sliding carriage, a carriage release lever, a margin stop rod, and a center stop, of margin stop mechanism, comprising a settable stop, slidably mounted on said margin stop rod, means on said margin stop for releasably interlocking with said center stop when said stop members are mutually engaged, and means connected to said carriage release lever for operating said interlocking means, whereby, when said carriage release lever is manipulated, said margin stop may be set at a desired position on said margin stop rod by the subsequent movement of said carriage.
14. A margin stop mechanism for a typewriter, having in combination a settable margin stop adapted to be mounted on the margin stop rod of a typewriter, means on said margin stop for releasably interlocking with the center stop of said typewriter, and means for controlling said first mentioned means from an accessible point on a typewriter, whereby said margin stop may be set at various positions on said margin stop rod by the movement of said carriage.
15. In a typewriter having a movable carriage, an adjustable stop element releasably fixed on a support to engage said carriage and limit the movement thereof, and means to simultaneously release said carriage and release said stop member for movement on its support, whereby said stop member may be automatically shifted by the movement of said carriage after engagement therewith.
16. In a typewriter having a movable carriage, and a carriage release lever, an adjustable margin stop releasably fixed on a support and adapted to engage said carriage

- and limit the movement thereof, said carriage release lever being operative to simultaneously release said carriage and said margin stop from its support whereby said margin stop may be engaged by said carriage and automatically shifted by the movement of said carriage.
17. In a typewriter, the combination with a sliding carriage, a carriage release lever, 10 a margin stop rod and a center stop, of margin stop mechanism comprising an adjustable stop slidably mounted on said margin stop rod, a laterally projectable member on said adjustable margin stop adapted to releasably interlock with said center stop when said stop members are mutually engaged, and means for operating said member and releasing said adjustable margin stop from
- said carriage release lever whereby said adjustable margin stop may be set at a desired position by the subsequent movement of said carriage.
18. In a typewriter, the combination with a sliding carriage, an escapement pinion for controlling the movement thereof, and a center stop, of margin stop mechanism comprising an adjustable margin stop, means for simultaneously disengaging said carriage from said escapement pinion and interlocking said margin stop with said center stop whereby when said carriage is moved said margin stop may be adjusted and set at a desired position.

In testimony whereof I affix my signature.

JAMES A. RAMUS.
